E. E. SANDERS.
AUTOMATIC ADJUSTABLE HEADLIGHT.
APPLICATION FILED SEPT. 27, 1915.

Patented July 31, 1917.

UNITED STATES PATENT OFFICE.

EMERSON E. SANDERS, OF CHATTANOOGA, TENNESSEE.

AUTOMATIC ADJUSTABLE HEADLIGHT.

1,235,058.

Specification of Letters Patent. Patented July 31, 1917.

Application filed September 27, 1915. Serial No. 52,828.

To all whom it may concern:

Be it known that I, EMERSON E. SANDERS, a citizen of the United States, residing at Chattanooga, in the county of Hamilton and 5 State of Tennessee, have invented certain new and useful Improvements in Automatic Adjustable Headlights, of which the following is a specification.

My invention relates to an automatically 10 actuated dirigible headlight, particularly adapted for use on rapidly moving vehicles such as locomotives and the like.

One object of my invention is the provision of a headlight of the character above 15 mentioned which is controlled by electrically energized actuating means which acts to swing the headlight so that the beam projected thereby will always travel in the direction in which the vehicle is moving; and 20 will not, as in the case with a fixed headlight, be projected tangentially of the path of movement of the vehicle when the latter is rounding a curve.

Another object of my invention resides 25 in the provision of novel solenoid means for actuating the headlight.

And a still further novel feature of my 30 invention resides in the provision of a novel distributing and controlling switch for said solenoid means.

Other objects and novel features of my invention will be apparent from the following description taken in connection with the accompanying drawing forming a part of 35 this specification, and in which I have illustrated one embodiment of my invention which I have found in practice to give good results.

In the drawings: 40 Figure 1 is a side elevation of a locomotive provided with a dirigible headlight constructed according to my invention.

Fig. 2 is a top plan view of the locomotive and headlight shown in Fig. 1.

Fig. 3 is a detail plan view of the distributing and controlling switch for the solenoid actuating means; and

Fig. 4 is a diagrammatic view showing the 50 wiring diagram for the headlight, switch, and solenoid means.

In detail:

The drawings illustrate the forward portion of a locomotive A including a boiler body 1 and forward truck 2. Upon the 55 boiler body 1, forwardly of the smoke-stack 3, is pivotally mounted a headlight 4, the

pivot post 5 being carried directly upon the body 1. Back of the headlight 4 is a second pivot post 6 carrying a bell crank lever 7, the long arm of which is slotted as shown at 60 8, whereas the short arm carries a pin 9 engaging in a slot 10 in a tongue 11 on the headlight 4. Thus, as the bell crank lever 7 is moved, the headlight 4 will be turned to the right or the left as the case may be. 65

In order to turn the headlight, the solenoid means B is provided, and this consists of a plurality of hollow non-magnetic rings 12, each provided with a winding 13 consisting of a suitable number of turns. The 70 rings 12 form a cylinder in which an armature 14 fits as shown in dotted lines in Fig. 4; thus, the armature 14 will move back and forth in the cylinder, depending on the coil which is energized. The armature 14 carries a rod 15 provided at its outer end with a link 16 connected by means of a pin 17 with the bell crank lever 7. The pin 17 is adjustable in the slot 8 by means of any suitable arrangement and thus, the operative 75 length of the long arm of the bell crank lever 7, may be shortened or lengthened as conditions may require.

To properly energize the different coils of the solenoid relay B, any suitable source 80 of current, such as a dynamo C, may be provided, it being understood that this source of current may be either a storage battery or wet cell of any type, one pole of which is in electrical communication with a 85 wire 18 which, in turn is in communication with one pole of each of the coils 13, whereas the other poles lead to segments 19 of a distributing switch, one being provided for each coil. These segments are insulated 90 from one another and are arranged on an arc having as its center the axial line of the forward truck 2. These segments are carried by a bracket 20 bolted to the frame 95 of the locomotive and the wires lead through a tube 21 to the solenoid relay B. To complete the distributing switch designated as 100 D, a contact member 22 is provided which has its shank 23 journaled in the bracket 24 mounted on the frame of the truck 2 and on a radial line with respect to the arc of the segments 19. To insure contact of the member 22 a spring 25 is provided which is positioned between bracket 24 and the head of the contact member 22. The segments 19 105 are of sufficient height to compensate for the relative vertical movement between con-

tact member 22 and said segments 19, and the spring 25 takes care of any lateral movement. The shank 23 is in connection with the remaining pole of the source of current C, and thus as the truck 2 moves when the locomotive is rounding a turn the contact member 22 will pass successively over the segments 19 energizing their respective coils 13 and drawing the armature 14 in the proper direction to move the headlight 4 to the left or right dependent upon the direction in which the locomotive turns.

It will be evident from the foregoing description that I have provided an automatically actuated dirigible headlight of simple construction. However, it is to be understood that I do not wish to be limited to the specific construction herein described except in so far as the appended claims import.

Also it will be evident that gears instead of levers may be provided to connect the armature with the headlight, and that the solenoid may extend either longitudinally 25 or transversely of the engine body 1.

I claim:

1. An automatically actuated dirigible headlight for vehicles comprising a pivotal support for said headlight, an electrically reciprocated armature, levers connecting said headlight with the armature for turning movement by the latter, and means including a source of electrical energy for moving said armature to selected positions, substantially as described.

2. The combination with a pivotally mounted headlight for vehicles, of means

for directing the beam projected thereby into the path of the vehicle when the latter is rounding a turn, said means comprising an electrically actuated reciprocable member including lever means connecting said member and headlight, substantially as described.

3. The combination with a pivotally mounted headlight for vehicles, of means for directing the beam projected thereby into the path of the vehicle when the latter is rounding a turn, said means comprising an electrically actuated reciprocable member including lever means connecting said member and headlight, and means co-acting with the running gear of the vehicle to control the movement of said reciprocable member, substantially as described.

4. An automatically actuated dirigible headlight for vehicles, comprising, a pivotally supported headlight, a bell-crank lever having one arm in connection with said light, a reciprocable arm in connection with the other arm of said bell-crank lever, a plurality of aligned hollow cylindrical magnets forming a cylinder receiving the free end of said reciprocable arm, and mechanism for selectively energizing said magnets to move said arm inwardly and outwardly to swing said headlight.

In testimony whereof I hereunto set my hand in the presence of two subscribing witnesses.

EMERSON E. SANDERS.
